CLAIM

The ornamental design for a computer display panel with graphical user interface comprising a set of images for a fashion gallery, as shown and described.

DESCRIPTION

FIG. 1 is a front view of a computer display panel with graphical user interface showing a first image of the set; FIG. 2 is a front view thereof showing a second image of the set;

FIG. 3 is a front view thereof showing a third image of the set;

FIG. 4 is a front view thereof showing a fourth image of the set;

FIG. 5 is a front view thereof showing a fifth image of the set;

FIG. 6 is a front view thereof showing a sixth image of the set; and,

FIG. 7 is a front view thereof showing a seventh image of the set.

The broken lines in the drawings illustrate a computer display panel and form no part of the claimed design.

The claimed design is directed to the collective appearance of the set of images of the graphical user interface.
